UNITED STATES PATENT OFFICE.

PATRICK DILLON, OF MILFORD, MASSACHUSETTS.

BOTTLE-STOPPER.

SPECIFICATION forming part of Letters Patent No. 591,824, dated October 19, 1897.

Application filed November 9, 1896. Serial No. 611,464. (No model.)

To all whom it may concern:

Be it known that I, PATRICK DILLON, of Milford, in the county of Worcester and State of Massachusetts, have invented an Improvement in Bottle-Stoppers, of which the following description, in connection with the accompanying drawings, is a specification, like letters on the drawings representing like parts.

10 It is a great desideratum to provide a bottle which may be filled but once, and that before the bottle is stoppered, and which when emptied cannot be again used.

In my invention I provide a stopper which 15 may be inserted after the bottle has been filled, the putting of the stopper in the neck of the bottle automatically locking the stopper in place, so that it cannot be detached from the bottle without breaking the latter

20 or utterly destroying the stopper.

The stopper consists, essentially, of a hollow cap-shaped shell and depending spring-catches, the said catches containing between them a seat provided, preferably, with a conical opening in which is placed a conical valve which is seated by its own weight when the bottle is right side up, but which when the bottle is inverted will leave the said seat and permit the liquid to escape.

30 The cap has a discharge-orifice, and has located inside of it and between it and the valve a guard which is so located as to prevent one from tampering with the valve through said orifice.

35 Figure 1 shows in section part of a bottle stoppered in accordance with my invention; Fig. 2, a section on the line *x*, Fig. 1, looking above the said line; Fig. 3, a section looking below said line. Fig. 4 shows the neck 40 of the bottle inverted. Fig. 5 shows a modification, and Fig. 6 shows the cap of the stopper and the arms and guard.

The bottle *A*, of glass and of any usual or suitable shape, has a neck *A'*, and between 45 the mouth of the neck and the body of the bottle I provide a suitable shoulder, as *a*, Figs. 1 and 4, or *b*, Fig. 5.

My improved stopper is composed of a cap *d*, having a discharge-orifice which is stopped 50 temporarily with a plug *d'*.

Within the cap I have fixed a guard *c*, having two depending spring-arms *c'*, provided

with hooked ends *c*², which when the stopper, of which the said arms form a part, is inserted in the neck of the bottle, slip past 55 and automatically engage the shoulder *a* or *b*, thus locking and securing the stopper in the neck of the bottle.

The guard *c* is so located with relation to the cap and its discharge-orifice as to prevent the insertion of any tool or other object through said discharge-orifice to come in contact with the conical valve *e*, which rests in the valve-seat *e'* whenever the bottle is in upright position, as in Figs. 1 and 5. This 60 guard *c* does not, however, prevent the discharge of the liquid from the bottle when the plug has been removed, for the liquid passes about the guard and enters said discharge-orifice whenever the bottle is inverted 70 or tipped over.

The valve-seat is made cylindrical externally and is grooved at its sides to fit over and contain the spring-arms *c'* and leave them room to play in use.

75 The valve-seat may be of wood, cork, india-rubber, or glass, and so may be the valve, and preferably the upper end of the valve will have a projection of some sort, as at 2, to contact with the guard when the bottle is inverted 80 and keep the discharge-space open.

The outer side of the cap is inclosed by a jacket *f*, which may be of cork, india-rubber, or any other suitable material, the said jacket extending substantially to the lower end of the 85 valve-seat, and forming a packing between the metallic or wooden parts of the stopper and the inner side of the neck.

When the stopper has been inserted into a filled bottle, the top of the cap will be pushed 90 into the neck far enough to place the plug *d'* below the top line of the neck, and then I seal the stopper in the neck by any suitable sealing-wax or equivalent.

To remove the liquid from the bottle, the 95 user must first break through the seal and engage and withdraw the small plug, and then by tipping over the bottle the valve will automatically drop from the seat, leaving the liquid a chance to be poured out.

100 The spring-arms are so stiff that once engaged with the shoulder *a* or *b* the stopper cannot be drawn out of the bottle without breaking it, and hence the said bottle could

not be refilled with a different liquid and palmed off as the genuine liquid of a particular manufacturer owning and using the particular stopper which is a guarantee of the 5 genuineness of the liquid.

Having described my invention, what I claim as new, and desire to secure by Letters Patent, is—

- 10 1. A bottle-stopper composed of a valve-seat, a coöperating valve in said seat, a cap having a discharge-orifice, said cap inclosing said valve and valve-seat and spring-arms passing down the outer sides of said valve-seat to engage a shoulder inside the bottle 15 to lock the said stopper in place in the bottle-neck, combined with a plug inserted in the orifice of said cap, the said plug being adapted to be sealed in the neck of the bottle, substantially as described.
- 20 2. A bottle-stopper composed of a valve-seat, a coöperating valve in said seat, a cap having a discharge-orifice, said cap inclosing said valve and valve-seat, a guard between said valve and said discharge-orifice, and 25 spring-arms carried by said guard and passing down the outer sides of said valve-seat to en-

gage a shoulder inside the bottle to lock the said stopper in place in the bottle-neck, combined with a plug inserted in the orifice of said cap, the said plug being adapted to be sealed in the neck of the bottle, substantially as described.

3. A bottle-stopper composed of a valve-seat, a coöperating valve in said seat, a cap having a discharge-orifice, said cap inclosing 35 said valve and valve-seat, a guard between said valve and said discharge-orifice, and spring-arms carried by said guard and passing down the outer sides of said valve-seat to engage a shoulder inside the bottle to lock the 40 said stopper in place in the bottle-neck, combined with a plug inserted in the orifice of said cap, the said plug being adapted to be sealed in the neck of the bottle, and a jacket *f*, substantially as described.

In testimony whereof I have signed my name to this specification in the presence of two subscribing witnesses.

PATRICK DILLON.
